DESIGN FOR A CLOCK CASE

Max Schlenker, La Salle, Ill., assignor to Western Clock Company, Peru, Ill., a corporation of Illinois

Application January 23, 1936, Serial No. 60,738

Term of patent 7 years

To all whom it may concern:

Be it known that I, Max Schlenker, a citizen of the United States, residing in the city of La Salle, in the county of La Salle and State of Illinois, have invented a new, original, and ornamental Design for Clock Cases, of which the following is a specification, reference being had to the accompanying drawing, forming a part thereof.

In the drawing:

Figure 1 is a perspective view of a clock case,
showing my new design.

Figure 2 is a front view of same.

Fig. 3 is a side view of the opposite side of the clock case shown in Fig. 1. Figs. 2 and 3 are drawn on slightly reduced scales.

I claim:

The ornamental design for a clock case, as shown and described.
